UNITED STATES PATENT OFFICE

123,596

DESIGN FOR A BASE FOR A TABLE CENTER- PIECE

Emil Edward Hornung, Jacksonville, Fla.

Application September 23, 1940, Serial No. 95,305

Term of patent 14 years

To all whom it may concern:

Be it known that I, Emil Edward Hornung, a citizen of the United States, residing at Jacksonville, in the county of Duval and State of Florida, have invented a new, original, and ornamental Design for a Base for a Table Centerpiece, whereof the following is a specification, reference being had to the accompanying drawing, forming part thereof.

In the aforesaid drawing:

Fig. 1 is a top plan view of a base for a table centerpiece showing my new design, and

Fig. 2 is a side elevational view thereof.

I claim:

The ornamental design for a base for a table centerpiece, as shown.

EMIL EDWARD HORNUNG.
